ORTHOPEDIC DEVICE

Maria T. Laffin, North Hollywood, Calif.

Application June 20, 1949, Serial No. 100,191

2 Claims. (Cl. 128—76)

1

The invention relates to an upper lip supporter, and more especially to a mouth applicator for bracing the upper lip of a person for eliminating deformities in the outward appearance or expression to the mouth.

In the course of human life, due to nervous strains and mental stresses imposed on the person, especially during early and middle ages, it being a habit for such a person, either while sleeping or awake, when under tense moments to tighten the upper lip of the mouth or cause it to pucker, contract or otherwise become distorted from normalcy, and if this condition continues periodically or otherwise the upper lip permanently acquires wrinkles or outer skin lines or a drawn expression which becomes set and thus the normal expression of the mouth becomes disfigured and contracted from the natural composure, especially of the female with resultant disturbance to the beautifying appearance of the person.

The primary object of the invention is the provision of an applicator of the character named, wherein the foregoing habit and resultant affects will be resisted and relieved so that the upper lip of the mouth under the use of the said applicator will retain a natural composure, irrespective of the stresses and strains during tense moments, thus assuring firmness to the lip and without puckering, wrinkling, contracting or otherwise deformation to the said lip resultant in maintaining a passive appearance or expression of the same.

Another object of the invention is the provision of an applicator of this character, wherein the inherent quality of its make-up will not injure the membranes or inner walls of the upper lip, the area adjacent to the latter and the upper jaw gum or the teeth, it conforming to the area between such lip and jaw, and having resiliency, flexibility and elasticity, so as to adapt itself to the jaw and lip contour, yielding to lip motion and its return to normalcy, the applicator being such that it will afford protection to the gum for excluding contamination by food substance accumulation in crevices or pockets between the teeth and the meeting edge of the gum therewith or the trapping of injurious matter thereby.

A further object of the invention is the provision of an applicator of this character, wherein when it is worn there will be no interference with speech, eating, drinking etc., and it will anchor itself in place without fasteners or the like, as the said applicator is held firmly and comfortably between the upper lip and jaw by vacuum indentations, so that it will not drop, slip or become displaced while in the mouth of a user.

A still further object of the invention is the provision of an applicator of this character, wherein it is partially pervious to a medicament,

2

antiseptic solution, breath purifier, or other mouth freshening liquids, and avoids accumulation of saliva, germ breeding and other unsanitary conditions in the mouth, thus rendering it healthy.

A still further object of the invention is the provision of an applicator of this character, wherein it can be readily and conveniently cleaned and may be placed in and removed from the mouth with ease and dispatch.

A still further object of the invention is the provision of an applicator of this character, which is simple in construction, thoroughly reliable and effective in purpose, strong, durable, light in weight, it being concealed from view while being worn, and is devoid of detracting from the normal expression or displeasing appearance to the mouth, as well as susceptible of manufacture at a minimum expense, either by special order or custom-make.

With these and other objects in view the invention consists in the features of construction, combination and arrangement of parts as will be hereinafter more fully described in detail, illustrated in the accompanying drawing, which discloses the preferred embodiments of the invention, and pointed out in the claims hereunto appended. It is to be understood that changes, variations and modifications may be made in the invention, as fall properly within the scope of the annexed claims, without departing from the spirit of the invention or sacrificing any of its advantages.

In the accompanying drawing:

Figure 1 is a partial diagrammatic side elevation of a human head showing the applicator constructed in accordance with the invention associated therewith and in wearing position.

Figure 2 is a front elevation of the applicator removed from the mouth of the head.

Figure 3 is a rear elevation of the applicator.

Figure 4 is a lowermost edge view of the same.

Figure 5 is a fragmentary sectional view taken approximately of the line 5—5 of Figure 3 looking in the direction of the arrows and of slightly larger scale.

Figure 6 is a view similar to Figure 5, showing a slight modification.

Similar reference characters indicate corresponding parts throughout the several views in the drawing.

Referring to the drawing in detail, A designates generally the mouth applicator or upper lip support constituting the present invention and involves a membranous element which may be formed of a somewhat flexible, resilient and preferably elastic material or materials. Sponge rubber has been found highly satisfactory, yet it may be made from fibrous material, such for example as cotton, bat or any suitable material

that will satisfy the demands of the applicator or support in the use thereof for the purposes intended of the same. This element denoted at 10 may be or is initially curved to correspond approximately to the external or labial curvature of the dental arches, and in the illustrated example it is further provided with impressions 11 corresponding in size and disposition to the fore normal maxilla teeth, these impressions 11 being located at the free lowermost edge 12 of the said element 10 and intersect such edge to partially overlie that area next to the gum at the meeting of the latter with the upper teeth and contacts against the outer surfaces of the same. The formation of the element 10 may be satisfactorily accomplished by depositing latex directly into a mold, preferably under pressure to insure evenness of texture, yet this element may be otherwise created to accord with the structural make-up of the applicator or support constituting the present invention, as hereinafter further described in detail.

The element in one instance has provided in one surface following the longitudinal extent thereof a plurality of spaced indentations forming vacuum pockets or cups 13, which are adapted to operatively hold the element in the space between the upper jaw and the upper lip and following the dental arch of the wearer, while the impressions 11 having contact with the teeth of the upper jaw further serve to hold and prevent slipping of the element downwardly from between the said upper lip and jaw. In another instance the pockets or cups 14 will be present in the outer surface of the element 10, as shown in Figure 6 of the drawing, and these serve the same purpose as the pockets or cups 13 before described.

In Figures 1 and 5 of the drawing it will be noted that in the illustrated instances the maximum portion of the element 10 is disposed against labial side of the upper jaw above the teeth and with slight overlap of the latter and resiliently held thereagainst owing to the inherent resilience of the element 10 itself, the latter being provided with a central notch 15 to avoid interference with the fraenum which extends medially between the upper lip and gum of the wearer, and this functions to prevent lateral creeping of the element 10 in the mouth during its use.

The element 10 by reason of the character or nature of the material from which the same is made is susceptible of slight absorption quality, so that it is partially pervious to a medicament, antiseptic solutions, breath purifiers, or other mouth freshening liquids and avoids accumulation of saliva, germ breeding and unsanitary conditions in the mouth, thus rendering it healthy.

It is preferable to have the element colored to correspond to the tint of the natural gums of the mouth so as to give a pleasing appearance both to the latter and the said element 10. This element 10 may have a film covering 16 of any selected material, so as to give smoothness thereto, the film covering 16 being disclosed in Figure 6, of the drawing, and such film need not overlie the cups or pockets 13 and 14, respectively, so that the absorption quality of the element need not be interfered with during the use of the said element 10. It should be noted that no extraneous

fastening means is employed with the element 10 to assure against displacement of the latter when placed between the upper lip and the opposed upper jaw and the corrective action of this element 10 is markedly a persuasive rather than a coercive one, the pockets or cups 13 and 14, with the notch 15 being double assurance against displacement.

The element 10 when applied in the mouth of a user as hereinbefore described will resist the contracting, puckering or otherwise distortion of the upper lip from a normal condition, which occurs during tense moments, and in this manner avoids the said upper lip permanently acquiring wrinkles or outer skin lines or a drawn expression which becomes set and thus the normal composure of the mouth will have become disfigured. Therefore, the applicator A constructed in accordance with the invention will brace the upper lip of a person for eliminating deformities in the outward appearance or expression of the mouth.

What is claimed is:

1. An orthopedic device for removable mounting in a mouth of a patient between an upper lip, upper teeth and upper gum, respectively, comprising: a flexible and resilient membranous liquid absorbent element forming a pad-like body of a depth and width sufficient to cover the entire frontal area between the upper lip and dental arch of the upper gum with the lowermost portion only partially overlapping the upper teeth for exposing freely the biting edges of the latter, the said lowermost portion of the body being provided with a formation of a contour conforming to normal maxilla teeth and gum at points adjacent to each other, and means on said element for attaching said element to the upper gum of the wearer, said element having a smooth film covering, forming the lip engaging portion thereof.

2. An orthopedic device for mounting in a mouth of a patient between an upper lip, upper teeth and upper gum, respectively, comprising: a flexible and resilient membranous liquid absorbent element forming a pad-like body of a depth and width sufficient to cover the entire frontal area between the upper lip and dental arch of the upper gum with the lowermost portion only partially overlapping the upper teeth for exposing freely the biting edges of the latter, the said lowermost portion of the body being provided with a formation of a contour confronting the normal maxilla teeth and gum at points adjacent to each other, a central notch formation at the upper edge of the body for the fraenum medially between the upper lip and gum of a patient, the gum contacting portion of said body being provided with depressions to effect vacuum anchoring action on the mouth areas next thereto, said element having a smooth film covering, forming the lip engaging portion thereof.
